MINERALS SEPARATOR

William A. E. Hult, San Diego, Calif.

Application March 30, 1953, Serial No. 345,458

5 Claims. (Cl. 209—464)

1

The present invention relates generally to gravity separators and more particularly to a minerals separator for recovering valuable minerals from gravels and crushed ores.

The primary object of this invention is to provide a minerals separator which will segregate valuable minerals from a mixture of crushed ores in water.

Another object of this invention is to provide a minerals separator wherein novel and efficient means is provided for discharging the fines, with a limited quantity of middlings, into a separate compartment or launder, together with means for emptying this launder.

Another object is to provide a gravity separator for use with minerals and wherein provision is made for collection of the fines without the usual laborious flushing and cleaning of the equipment.

Still another object of this invention is to provide for recovery of fines mixed with only a small quantity of less concentrated materials.

Finally, it is an object to provide a minerals separator of the aforementioned character which is simple, safe and convenient to operate, and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawings which form a material part of this disclosure and wherein similar characters of reference indicate similar or identical elements and portions throughout the specification and throughout the views of the drawings, and in which:

Fig. 1 is a perspective view of the minerals separator.

Fig. 2 is a longitudinal sectional view of the device.

Fig. 3 is a sectional view taken on the line 3—3 of Fig. 2.

Fig. 4 is a fragmentary plan view of the device.

Fig. 5 is an end elevation view of the device.

Fig. 6 is an isometric view of the riffle board used in the machine.

Referring now to the drawing, the machine comprises, in brief, a base 10 on which is secured a lower launder 12 having a screw conveyor 14, and an upper launder 16 having a screw conveyor 18. The upper launder 16 is positioned directly above the lower launder 12 and is separated therefrom by a sliding riffle board 20. One end of the upper launder 16 is provided with a hopper 22 having an oscillating screen 24 to separate the coarser material before the ore is fed into the machine.

2

The base 10 includes a base plate 26 having a pair of support beams 28, the lower launder 12 being secured to said base plate by means of support webs 30. The lower portion of the lower launder is semicircular in shape to fit closely around the screw conveyor 14, the upper portion of said lower launder being open. The screw conveyor 14 is carried on a shaft 32 which is supported at one end in a bearing 34 on the end plate 36, and is supported at the other end in a bearing 38 attached to the support plate 40, which also closes and supports the lower launder.

It should be noted that the end of the lower launder beneath the end plate 36 is open as indicated at 41 to allow the expulsion of the fines or concentrates.

The upper launder 16 comprises a pair of sides 42 having downwardly extended portions 44 secured to the base plate 26, and an end 46 which also extends to the base of the machine. The lower portion of the upper launder 16 is tapered inwardly and comprises the sloping sides 48 and 50, the remaining end of said upper launder being supported on the lower launder 12 by a web 52. The sides 42 are held in spaced relation by the end plate 54, having thereon the bearing 56 which carries the drive shaft 58 on which the screw conveyor 18 is secured. The other end of the drive shaft 58 is supported in the bearing 60 fastened to the end 46, said drive shaft having thereon a pulley 62 which is connected by means of a drive belt 64 to a suitable motor (not shown).

The drive shaft 58 is also provided with a pulley 66 which carries a belt 68 engaging with the pulley 70 secured to the shaft 32, so that both screw conveyors are simultaneously rotated. The upper and lower launders are separated by the riffle board 20, which fits between the support plate 40 and the web 52, and slides on a pair of rails 72 fitted flush with the upper edges of the lower launder 12. The rails 72 extend outwardly on one side of the machine and are fitted with end stops 74 to limit the travel of the riffle board 20.

The riffle board has on its upper surface a plurality of riffles 76 which extend to one side of said riffle board and pass through corresponding notches 78 in the sloping side 50, the other ends of said riffles being chamfered as indicated at 80 to butt against the sloping side 48 when the riffle board is closed as shown in Fig. 3. The lower surface of the riffle board 20 has two toothed racks 82 which are engaged by the pinions 84 on the actuating shaft 86, said actuating shaft being supported at one end in the bearing 88 attached to the support plate 40, and at the other end in a bearing 90 carried on the extended portion 92 of the end plate 36. The actuating shaft 86 is provided with a crank 94, so that by manual

rotation thereof, the rifle board 20 may be slid to one side.

The end of the upper launder 16 remote from the hopper is provided with a gate 96 which fits over the aperture 98 between the web 52 and the end plate 54, said gate being vertically slidably mounted in guides 100.

Attached to the gate 96 is a link 102 connected to a hand lever 104 which in turn is pivotally mounted on the side 42, so that by depression of said hand lever, the gate 96 may be raised to open the aperture 98.

The upper launder 16 is provided with a discharge chute 106 shaped to fit around the aperture 98, so that rough material expelled therefrom will be carried clear of the machine.

The hopper 22 is attached to the upper edges of the upper launder 16 and comprises two sides 108 and an end 110. The screen 24 has a frame 112 which is slidably mounted in guides 114 attached to the sides 108, said frame protruding through a slot 116 in the end 110. The open end of the hopper 22 has a discharge lip 118 secured between the extended sides 108, so that rough ores retained on top of the screen 24 will be prevented from falling into the upper launder and will be carried clear of the machine.

The screen 24 is oscillated by a connecting rod 120 pivotally attached thereto, said connecting rod being eccentrically fastened to a disc 122 on the shaft 124 which is rotatably mounted on the bracket 126. The shaft 124 is provided with a pulley 128 having thereon a belt 130, which is driven by a pulley 132 on the drive shaft 58, thus the screen 24 is oscillated continuously while the machine is in operation.

In order to separate concentrates from ores, the crushed ores, gravels or the like or fed into the hopper, together with water, while the machine is in operation. The screen 24 sifts the finer ores and allows them to fall into the upper launder 16, where the screw conveyor 18 agitates the ores and the water causing the heavier particles to settle at the bottom of the launder. These heavier particles are the valuable minerals sought to be recovered, being considerably heavier than the ores in which they are found. These valuable fines or concentrates collect between the riffles 76 while the tailings, or unwanted ores, are piled up at the end of the upper launder adjacent the aperture 98, a certain amount of the excess being ejected over the end plate 54. As soon as sufficient ore has been segregated, the feeding of ores into the hopper is stopped, the gate 96 is opened, and continued rotation of the screw conveyor 18 expels the tailings from the chute 106.

The rifle board 20 is now opened so that the fines or concentrates between the riffles 76 are scraped off and fall into the lower launder, where the screw conveyor 14 expels them through the open end 41 from where they are collected in suitable containers.

A fresh load of ores is now fed into the hopper 22 and the process repeated, or if desired, the original ores may be fed through the machine again for additional segregation.

The machine is, of course, driven by means of a suitable motor of any well known type.

It will be seen that the moving parts of the machine are few and the construction simple, the machine being easily serviced and cleaned.

The operation of this invention will be clearly comprehended from a consideration of the foregoing description of the mechanical details thereof, taken in connection with the drawing and

the above recited objects. It will be obvious that all said objects are amply achieved by this invention.

Further description would appear to be unnecessary.

It is understood that minor variation from the form of the invention disclosed herein may be made without departure from the spirit and scope of the invention, and that the specification and drawing are to be considered as merely illustrative rather than limiting.

I claim:

1. A minerals separator comprising an upper launder having a screw conveyor, and a lower launder having a screw conveyor, a rifle board disposed in one position thereof between said upper and lower launders, a hopper at one end of said upper launder, a discharge chute at the other end thereof, and an outlet in said lower launder, said rifle board being shiftable to a second position, and means to unload fines and concentrates gathered on said board into the lower launder when the board is shifted to said second position.

2. A minerals separator comprising an upper launder having a screw conveyor, and a lower launder having a screw conveyor, a rifle board slidably mounted between said upper and lower launders, a crank operatively connected with said rifle board whereby said board can be shifted to deposit the contents of said upper launder in said lower launder, a hopper at one end of said upper launder, a discharge chute at the other end thereof, and an outlet in said lower launder.

3. A minerals separator comprising an upper launder and a lower launder below the upper launder, a rifle board disposed in one position thereof between said upper and lower launders, said rifle board being shiftable to a second position, said upper launder having a fixed side with portions extending downwardly between said riffles, said portions comprising fixed scrapers to dislodge the fines from the rifle board when it is shifted toward said second position.

4. A minerals separator comprising an upper launder having a screw conveyor, and a lower launder having a screw conveyor, a rifle board slidably mounted between said upper and lower launders, a crank operatively connected with said rifle board whereby said board can be shifted to deposit the contents of said upper launder in said lower launder, a hopper at one end of said upper launder, an oscillating screen in said hopper, a discharge chute at the other end of said upper launder, and an outlet in said lower launder.

5. A minerals separator comprising an upper launder having a screw conveyor, and a lower launder having a screw conveyor, a rifle board slidably mounted between said upper and lower launders, a crank operatively connected with said rifle board whereby said board can be shifted to deposit the contents of said upper launder in said lower launder, a hopper at one end of said upper launder, an oscillating screen in said hopper, a discharge chute at the other end of said upper launder, a gate slidably mounted at said other end of the upper launder to control the flow of material from the upper launder into said chute, and an outlet in said lower launder.
